(57) **CLAIM**

The ornamental design for a dual door microwave oven, as shown and described.

DESCRIPTION

FIG. 1 is a front perspective view of a dual door microwave oven showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top plan view showing both doors in an open configuration.

The broken lines in the drawings illustrate environmental structure on the article and form no part of the claimed design.
